No. 881,048.

PATENTED MAR. 3, 1908.

W. H. BETTS.
STEAM ENGINE.
APPLICATION FILED JUNE 4, 1907.

UNITED STATES PATENT OFFICE.

WALTER H. BETTS, OF ADMIRE, KANSAS.

STEAM-ENGINE.

No. 881,048.

Specification of Letters Patent. Patented March 3, 1908.

Application filed June 4, 1907. Serial No. 377,215.

To all whom it may concern:

Be it known that I, WALTER H. BETTS, a citizen of the United States, residing at Admire, in the county of Lyon and State of Kansas, have invented new and useful Improvements in Steam-Engines, of which the following is a specification.

This invention relates to a double-acting engine of that type in which the admission and exhaust of the motive fluid to and from the cylinder are controlled by the movement of the piston, whereby the more or less complicated valve mechanism commonly employed is dispensed with.

The invention has for one of its objects to improve and simplify the construction and operation of engines of this character so as to be comparatively easy and inexpensive to manufacture, thoroughly reliable and efficient in use, and readily controlled.

A further object of the invention is the provision of an engine within the cylinder of which is a hollow cylindrical member that receives the piston and is actuated at the end of each stroke of the latter for opening an inlet port on one side of the piston and simultaneously opening the exhaust port on the opposite side, so that the admission and exhaust of steam can be controlled automatically to effect the continuous operation of the engine.

A still further object is the employment of a reversing mechanism whereby the inner reciprocating cylinder can be adjusted to reverse the engine.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one of the embodiments of the invention, Figure 1 is a longitudinal vertical section of a single cylinder, double-acting engine. Fig. 2 is a longitudinal section of the inner cylinder or valve of the engine. Similar reference characters are employed to designate corresponding parts throughout the several views.

Referring to the drawing, 1 designates the bed of the engine; 2, the cylinder mounted at one end thereof and in which is a piston 3 that imparts rotation to the crank shaft 4, through the piston rod 5, cross-head 6, and

connecting rod 7, the cross-head being arranged to reciprocate in a guide 8 on the bed 1. These parts of the engine may be of any approved design as far as the present invention is concerned.

On the cylinder 2 is a steam chest 9 that is supplied with live steam by the pipe 10 that is provided with a controlling valve 11, and between the steam chest and cylinder 2 are inlet ports 12 spaced slightly inwardly from the heads of the cylinder to provide for the necessary compression at the ends of the strokes of the piston 3. Arranged at the opposite side of the cylinder or at any other suitable point are exhaust ports 13 to which are connected a branch exhaust pipe 14. The inlet and exhaust ports of the cylinder 2 are opened and closed by an inner cylinder 15 that constitutes a single valve for all the ports. The inner cylinder has a working fit in the main cylinder and is adapted to move back and forth therein and the piston 3 reciprocates within the inner cylinder which is carefully finished to insure a working fit with the piston. The hollow cylindrical valve 15 is provided with inlet ports 16, so arranged that one or the other can be brought into register with one of the inlet ports 12, so that steam can be admitted to one side of the piston while it is cut off from the other side. The member 15 is also provided with exhaust ports 17 arranged to register one at a time with the stationary exhaust ports 13 and the relation of the various ports is such that while steam is admitted to one side of the piston, it exhausts from the other side.

In the outer surface of the cylindrical valve 15 are annular grooves for receiving packing rings 18 for preventing leakage. Adjacent the ends of the valve 15 are internal stops, projections or abutments 19 disposed in the path of the pistons 3, so that as the latter nears the end of its stroke in either direction, it will engage one of the abutments 19 and impart longitudinal movement to the valve for simultaneously cutting off steam from one side and admitting it to the other side of the piston. In this manner, the valve is moved back and forth directly by the piston to control the admission and exhaust for effecting the continuous reciprocation of the piston.

In order to reverse the direction of movement of the engine, provision is made to shift the position of the valve 15, and for this purpose, the latter is provided with a

- central arm or post 20 having a threaded engagement with the inner valve or cylinder to permit the latter to be readily inserted into or removed from the cylinder 2. The 5 arm 20 passes through an opening 21 in the wall of the cylinder 2 and projects into the valve chest 9. The arm has an opening 22 for receiving the inner end of an actuating rod 23 that is provided with adjustable nuts 10 or stops 24 for engaging with the post 20 to shift the valve 15 in one direction or the other. The rod 23 extends through the wall of the steam chest and is hingedly connected with an operating lever 25 fulcrumed 15 on a bracket 26 carried by the rear head of the cylinder. The lever is provided with a latch 27 engaging a toothed section 28 on the bracket, whereby the lever can be held in adjusted position. Normally the valve 20 or inner cylinder 15 moves back and forth between the nuts 24 without interference, and by operating the lever 25, the valve 15 20 can be shifted so as to reverse the direction of travel.
- 25 When it is desired to reverse the engine and the piston is moving to the left as shown in Fig. 1, it is merely necessary to throw the lever 25 to such a position as to cause the left hand inlet port of the cylindrical valve 30 15 to register with the left hand port of the valve chest. This will admit steam to the left side of the piston and cut off the supply to the right side and thereby cause the engine to reverse. As soon as the piston starts 35 on its reverse stroke, the lever is adjusted and locked in such a position as to permit the valve 15 to be actuated by the piston, as before, whereby the engine will continue to operate in a reverse direction.
- 40 From the foregoing description, taken in connection with the accompanying drawing, the advantages of the construction and of the method of operation will be readily ap-

parent to those skilled in the art to which the invention appertains; and while I have 45 described the principle of operation of the invention, together with the apparatus which I now consider to be the best embodiment thereof, I desire to have it understood that the apparatus shown is merely illustrative 50 and that such changes may be made when desired as are within the scope of the claims.

Having thus described the invention, what I claim is:—

1. In an engine, the combination of a 55 cylinder having inlet and exhaust ports, a cylinder therein, having inlet and exhaust ports and movable longitudinally to alternately bring corresponding ports into register, a piston reciprocating in the inner cylinder and adapted to close the ports at the ends of the strokes, means on the inner cylinder for engaging the piston to receive motion therefrom, and a manual means for adjusting the inner cylinder to reverse the engine. 65

2. In an engine, the combination of a stationary outer cylinder having inlet and exhaust ports, an inner cylinder mounted for reciprocation and having ports adapted to register with those of the outer cylinder, a 70 piston reciprocating within the inner cylinder and adapted to impart motion thereto at the end of each stroke, a removable member on the inner cylinder and extending into the steam chest, an actuating rod, an adjustable 75 lost motion connection between the member and rod and located within the chest, and a manually actuated means connected with the rod for reversing the engine.

In testimony whereof, I affix my signature 80 in presence of two witnesses.

WALTER H. BETTS.
